Term of patent 14 years

Int. Cl. D17—03

U.S. Cl. D56—1

FIG. 1 is a top plan view of a combined tailpiece and adjustable bridge for a guitar or similar article, showing one form of my new design for use on a six-stringed guitar;

FIG. 2 is a front elevational view of the form shown in FIG. 1 with the adjustable bridge in its lowermost position;

FIG. 3 is a rear elevational view of the form shown in FIG. 1 with the adjustable bridge in its lowermost position;

FIG. 4 is a side elevational view of the form shown in FIG. 1, the opposite side being substantially a mirror image thereof;

FIG. 5 is a front elevational view of the form shown in FIG. 1 with the adjustable bridge in its uppermost position;

FIG. 6 is a top plan view of a combined tailpiece and adjustable bridge for a guitar or similar article, showing a second form of my new design for use on a 12-stringed guitar;

FIG. 7 is a front elevational view of the form shown in FIG. 6 with the adjustable bridge in its lowermost position;

FIG. 8 is a rear elevational view of the form shown in FIG. 6 with the adjustable bridge in its lowermost position;

FIG. 9 is an end elevational view of the form shown in FIG. 6, the opposite end being substantially a mirror image thereof; and

FIG. 10 is a front elevational view of the form shown in FIG. 6 with the adjustable bridge in its uppermost position.

I claim:

The ornamental design for a combined tailpiece and adjustable bridge for a guitar or similar article, substantially as shown and described.
